CLAMPING MEMBER FOR CLAMPING THE
ONE END OF A CORD, WHICH IS FIXEDLY
FASTENED TO THE CLAMPING MEMBER
WITH THE OTHER ENDJacobus Gerardus van den Bel, Overveen,
NetherlandsApplication March 10, 1933, Serial No. 660,324
In the Netherlands March 11, 1932

16 Claims. (Cl. 24—30.5)

When tying up bags and similar packings a string is laid around the open end of the filled bag, the ends of which are permanently fastened together by means of a seal of lead or of tin.

5 The tying up of a bag in this manner requires a large number of manipulations, to wit laying the string around the bag, tying the string, passing the string ends through the seal of lead or of tin, tying the string again and finally 10 clamping the seal of lead or of tin by means of sealing pliers.

It has already been proposed, in order to 15 simplify this series of manipulations, to use an auxiliary means, consisting of a cord, fixedly fastened with its one end to a holder in which a sealable cord clamp, consisting of two co-operating rollers, is arranged for clamping the end of the cord between these rollers.

Such an auxiliary means, however, is owing to 20 its construction too expensive to be applied for all purposes coming into consideration and besides it has the disadvantage that it has to be sealed separately and even then it does not offer a sufficient guarantee against loosening by unauthorized persons.

25 The object of the invention is to obtain an improved auxiliary means of this kind, in which the above objections are avoided and the subsequent sealing has become superfluous.

30 To this end, according to the invention, the clamping member is provided with a tubular portion having at the inside projections or barbs for only allowing the cord composed of intertwined threads to pass in one direction.

35 With reference to the drawing the invention will be illustrated by the description of some embodiments of the clamping member.

Fig. 1 is a perspective view of the first embodiment, of which

40 Fig. 2 is a longitudinal section on a larger scale;

Fig. 3 is a cross-section according to the line III—III in Fig. 2;

Fig. 4 is a perspective view of the second embodiment;

Fig. 5 is a section according to the line V—V in Fig. 4; while Figs. 6 and 7 disclose modified forms of the clamping device according to my invention.

50 According to the drawing the clamping member consists of a metal body 1, in which a tubular channel 2 is arranged, of which two opposing walls are provided with teeth or barbs 3 directed to each other, stamped out of the wall material.

55 The one end of a cord 4, composed of inter-

twined threads, is fixedly fastened to the clamping body 1.

When tying up a bag the free end of the cord is passed through the tubular channel 2 of the clamping member, in the direction of the barbs 3, after it has been wound one or more times around the bag.

When projecting from the other end of this channel, the end of the cord is caught and the clamping member is pushed over the cord, until the said member lies tightly against the bag.

If the clamping member is released it cannot slip back over the cord, as the barbs 3 immediately catch between the intertwined threads of the cord. Therefore the bag is definitely 70 closed and can only be opened again by cutting the cord.

Although, when using the clamping member, the cord can first be wound around the bag and subsequently passed through the tubular channel and tensioned, it is simpler to pass the cord first through the channel. In this manner a noose is formed, which can forthwith be thrown around the open bag end and subsequently pulled.

80 Since the bag, after the pulling of the noose, cannot possibly be opened without rendering the noose useless, the clamping member will at the same time serve as a seal which serves as a guarantee to the buyers of the bags or bales 85 that the contents of the same are untouched.

Another embodiment of the clamping member is also possible. The clamping member according to Figs. 4 and 5 is made of a single metal plate folded in such a way that two channels 90 are formed, the channel 5 serving for the permanent clamping of one end of the cord, while the channel 6 is provided with barbs for the one way passing of the other end of the cord.

It is however required that the cord consists 95 of intertwined threads. The material of these threads may be a fibre or a metal, dependent on the purpose in view.

It is furthermore possible to clamp the cord permanently in the channel 5 not with one end, 100 but at a point between the ends, one of the ends of the cord being provided with an eye, as in Fig. 6. Before passing the relative cord end through the channel 6, this end is first passed through the eye of the other end of the cord 105 and only then passed through the channel 6.

In this manner a loop is formed which, after the other end has been drawn through the channel 6, cannot be unfastened any longer and may serve for connecting together different objects, 110

e. g. the lugs of the door and the doorpost of a railway carriage for sealing said door.

Instead of providing one of the ends of the cord with an eye the cord may also be fixedly fastened in the channel 5 at a point between its two ends as well as with one of the said ends, as in Fig. 7, thus forming a double end of the cord from which a loop may be formed in a similar manner.

10 I claim:

1. A clamping member having a body with two channels, in one of which a cord is fixedly fastened, the other channel having inwardly projecting teeth.

15 2. A clamping member having a body with two channels, in one of which a cord is fixedly fastened at a point, between its ends and at one of its ends, thus forming a loop, the other channel having inwardly projecting teeth.

20 3. A clamping member having a body with two channels, in one of which a cord is fixedly fastened at a point between its ends, one of the ends of the cord being provided with an eye, the other channel having inwardly projecting teeth.

25 4. A clamping member for clamping a cord, comprising a body having two channels therein, one of which channels permanently secures the cord, and the other channel having permanent means therein for permitting the passage of the cord in but a single direction.

30 5. A clamping member for clamping a cord, comprising a body having two channels therein, one of which channels permanently secures the cord, and the other channel having barbs fastened therein for permitting the passage of the cord in but a single direction.

35 6. A clamping member for cords, comprising a body having two channels therein, in one of which the cord is permanently secured at one end, and permanent means in the other channel for permitting passage of the cord in but a single direction.

40 7. A clamping device, comprising a clamping member having a body with two channels therein, a fibrous cord permanently secured in one of said channels, and permanent means in the other of said channels for permitting passage of the said fibrous cord in but a single direction.

45 8. A clamping device, comprising a clamping member having a body with two channels therein, a cord permanently secured in one of said channels, and having a leader on one end thereof, and permanent means in the other one of said channels for permitting passage of the cord in but a single direction, the leader facilitating starting the cord through said last-mentioned channel in the desired direction.

50 9. A clamping device, comprising a clamping member having a body with two channels therein, a cord permanently secured in one of said channels, and having a leader on one end thereof, said leader having a length greater than the width of said clamping member, and permanent

means in the other one of said channels for permitting passage of the cord in but a single direction, the leader facilitating starting the cord through said last-mentioned channel in the desired direction.

80

10. A clamping device for clamping a cord, comprising a substantially flat, thin clamping member having two channel portions therein of diameter greater than the thickness of the said member, a cord permanently secured in one of said channels, and permanent means in the other of said two channels for permitting passage of the cord in but a single direction.

85

11. A clamping device, comprising a clamping member having two channels therein, a cord permanently secured intermediate of its length in one of said channels and having an eye formed on one end thereof, the other one of said channels having permanent means therein for permitting the passage of the other end of the cord therethrough in but a single direction.

90

12. A substantially flat, thin clamping member for clamping cords, having two channels formed therein of diameter greater than the thickness of said member, one of said channels being adapted to permanently secure a cord therein, and the other channel having permanent means for permitting passage of the cord in but a single direction.

95

13. A substantially flat, thin clamping member for clamping cords, having two channels formed therein of diameter greater than the thickness of said member, one of said channels being adapted to permanently secure a cord therein, and the other channel having barbs formed therein for permitting passage of the cord in but a single direction.

100

14. A clamping member for clamping cords, comprising a substantially parallelopiped body having two channels disposed entirely within the confines thereof, one of which is adapted to permanently secure a cord, and the other of which has means therein for permitting the passage of the cord in but a single direction.

105

15. A clamping device, comprising a clamping member having two channels therein, a cord permanently secured by one end and by a portion intermediate of its ends in one of said channels, the other one of said two channels having permanent means therein for permitting the passage of the other end of the cord therethrough in but a single direction, the said last-mentioned cord end being adapted to be first passed through the loop defined by the two said clamped portions of the cord.

110

16. A clamping device, comprising a clamping member having a substantially parallelopiped shape and having two channels disposed entirely within the confines thereof, a cord permanently secured in one of said channels having permanent means therein for permitting the passage of said cord therethrough in but a single direction.
